UNITED STATES PATENT OFFICE.

FRANK B. BLACK, OF GILBOA, OHIO.

SNARE-CURETTE.

932,103.

Specification of Letters Patent. Patented Aug. 24, 1909.

Application filed February 17, 1909. Serial No. 478,436.

To all whom it may concern:

Be it known that I, FRANK B. BLACK, a citizen of the United States, residing at Gilboa, in the county of Putnam and State 5 of Ohio, have invented certain new and useful Improvements in Snare-Curettes, of which the following is a specification.

This invention relates to certain new and useful improvements in surgical instruments, and comprises a snare curette.

The object of my invention is to provide a light, simply constructed and readily operative ecraseur, offering elective adjustments to the snares, so that they may be 15 brought below, above or to the side of the offending mass.

With these and other objects in view, the present invention consists in the combination and arrangement of parts, as will be 20 hereinafter more fully described and particularly pointed out in the appended claims, it being understood that changes in the specific structure shown and described may be made within the scope of the claims 25 without departing from the spirit of the invention.

In the drawings forming a part of this specification, and in which like numerals of reference indicate similar parts in the several 30 views:—Figure 1 shows a front view disclosing the curette in a closed position, Fig. 2 shows a front view disclosing the snares as opened, Fig. 3 is a closed edge view, Fig. 4 is a 35 face view disclosing the curette as unfolded, Fig. 5 discloses an outlined view showing the instrument inserted into the womb and under the offending mass, Fig. 6 discloses the plunger pushed up and shows the snares as open, Fig. 7 shows the snares turned up over the 40 offending mass and ready to be loosened, Fig. 8 discloses the snare as compressing the offending mass, Fig. 9 is a lower end view of the instrument as unfolded.

This invention relates to that class of 45 surgical instruments, which are used for scooping or scraping away or otherwise removing substances, such as granulations, cysts, or small polypi, from the cavity of the uterus.

50 My invention comprises two similar bars 5 and 6, which are rectangular in cross section, each terminating at one end in a curved finger hold 7. The opposite end of each bar is slotted and perforated as shown at 8 55 to provide two securing ears. One of these

bars or members as the one marked 6 is provided along one edge with the serrations 10. These members 5 and 6 are hingedly connected at their upper ends by means of a hinge 11 while at their lower ends the two 60 members are hingedly connected by means of the hinge 12. Slidably held upon each of these bars 5 and 6, is a sleeve 13, these sleeves also being hingedly connected by means of the hinge ears 14. As shown, each 65 one of these sleeves 13 is provided with a notch 15, and secured within these notches 15 at one end and the slots 8 at the other, are the two similar snares 16, which have their ends recurved in opposite directions 70 and arranged to be held within the slot and notch as shown. These snares are in the form of flat sharp edged spring members which are normally perfectly straight as disclosed. The normal position of the sleeve 75 13 is determined by these springs, which lie perfectly flat against the connected bars. As constructed, the lower entering end of the instrument presents a smooth and rounded surface. Secured to the sleeve 13, mounted 80 upon the bar 6 having the serrated edge 10 is a plunger rod 17, which is of such a thickness that when the instrument is in its folded position, as shown in Fig. 1, this plunger is squarely held between the two members. 85 This plunger is provided with the curved thumb hold 18 while intermediately of its ends it is provided with the collar 19 adapted to be brought into the serrations 10 in adjustably securing this plunger. As these 90 bars 5 and 6 are hingedly connected, each snare can be carried in an arc of ninety degrees.

The operative positions of the instrument in use are clearly disclosed in Figs. 5, 6, 7, 95 and 8. In Fig. 5, the curette is positioned below the offending mass α , the snares being in their normal position. In Fig. 6, the plunger has been advanced so as to open the snares with the snares in opposite directions 100 below the offending matter. In Fig. 7, the instrument has been turned to bring the snares in juxtaposition, while in Fig. 8, the plunger has been drawn outward so that the snares have been clasped upon the offending 105 matter.

The device is light, neat, and simple in construction. When the blades or snares have been compressed upon the offending matter, the mass is reduced in size and so 110

may be more easily removed. The snares when opened, or in their closed position may be held at any desired angle, and may be carried up and around any substance that 5 happens to be in the path of the snares. By releasing the plunger and making traction on the plunger, the mass may be securely held.

And having thus described my said invention, what I claim as new, and desire to secure by United States Letters Patent is:—

1. A snare curette, comprising two similar members hingedly connected, a plunger secured between said two members, a snare secured to each of said members, and means to connect the snares to said plunger.

2. A snare curette comprising two similar members hingedly connected at their upper and lower ends, a sleeve carried by each of 20 said members, a snare secured to the lower end of each of said members, and at their upper ends to one of said sleeves, and a plunger carried by one of said sleeves.

3. A snare curette comprising two similar 25 members hingedly connected, one of said members having a serrated edge, a sleeve carried by each of said members, a snare in the form of a flat spring secured to the lower end of each of said members, said snares at 30 their upper ends being secured to said sleeves, a plunger secured to one of said sleeves, and a collar carried by said plunger

adapted to engage the serrated edge of said member.

4. A snare curette comprising the combination of two similar members, a hinge connecting said members, one of said members having a notched edge, a sleeve carried by each of said members, a hinge connecting said sleeves, a snare in the form of a flat 40 spring secured at its lower end to the lower end of each of said members, the upper end of each snare being secured to one of said sleeves, a plunger secured to one of said sleeves, and a collar carried by said plunger 45 adapted to engage the notched edge of said member.

5. The combination in a curette, of two bar members hingedly connected along one edge, and a plunger slidably carried by one 50 of said members.

6. A snare curette comprising two similar members pivotally connected, a plunger secured therebetween, a snare connected to adjacent ends of each of the members and 55 slidable connections between the plunger and the snares.

In testimony whereof I affix my signature, in presence of two witnesses.

FRANK B. BLACK.
